United States Patent [19]

Terrazas et al.

[11] Des. 259,482

[45]  Jun. 9, 1981

[54] BICYCLE FRAME

[76] Inventors: Paul G. Terrazas, 45280 Kings St., Indio, Calif. 90212; Robert Terrazas, 2012 Nile St., Bakersfield, Calif. 93305

[] Term: 14 Years

[21] Appl. No.: 967,891

[22] Filed: Dec. 21, 1978

[51] Int. Cl. .... D12—11

[52] U.S. Cl. D12/111

[58] Field of Search .... D12/111; 280/281 R, 280/281 W

[56] References Cited

U.S. PATENT DOCUMENTS

3,595,599 7/1971 Black .... 280/281 W

FOREIGN PATENT DOCUMENTS

5531 2/1893 Sweden ..... 280/281 R
23873 of 1897 United Kingdom ..... 280/281 R

OTHER PUBLICATIONS

Playthings, 12/69, p. 52, bicycle #639-180, top left side of page.

J. C. Whitney Catalog No. 360B, ©1977, p. 143, Handlebar(l), top left side of page.

Primary Examiner—James M. Gandy
Attorney, Agent, or Firm—Poms, Smith, Lande & Rose

[57] CLAIM

The ornamental design for a bicycle frame, as shown and described.

DESCRIPTION

FIG. 1 is a side elevational view of a bicycle frame showing our new design, it being understood that the broken lines are for illustrative purposes only; and FIG. 2 is a perspective view thereof.